STRAINER UNIT

Martin E. Danills, Goodland, Kans.

Application September 10, 1932
Serial No. 632,606

3 Claims. (Cl. 210—169)

This invention relates to straining devices and pertains particularly to a strainer of the character used in association with internal combustion engines for straining the engine lubricating oil.

The present invention relates particularly to an improvement for an engine oil strainer of the type known commercially as a "Purolator." In these straining devices there is employed a fabric sack which envelops a spring body and which is secured at each of its ends to a plate which engages the adjacent end of the spring body. In each of these end plates is fixed a bushing which is employed for maintaining the straining bag or sack in proper position within the device. Each of these bushings holds a disk body in place against the adjacent plate and clamps against the plate the adjacent end of the straining bag. Since the bushing which maintains the disk and plates in operative relation is swaged over upon its inner end against the inner side of the adjacent plate, when the bag wears out or gets a hole in it so that it is no longer useful it is not possible to merely replace the bag but the entire unit must be discarded and a new one put in. Any attempt to remove the bushings so that a new bag may be placed upon the spring body will merely result in the damaging of the unit to such an extent that it can no longer be used.

The primary object of the present invention is to provide a bag unit in which the bushings may be readily removed from the end plates and the bag taken off and a new one put in its place, thus making it possible to renew the straining unit when a bag becomes worn out merely by replacing the bag instead of replacing the entire unit.

With the present invention the bushings at the end of the strainer unit are detachably coupled with the end plates and removably hold in place clamping disks which secure the ends of the bags in position.

The invention will be best understood from a consideration of the following detailed description taken in connection with the accompanying drawing forming part of this specification, with the understanding, however, that the invention is not confined to any strict conformity with the showing of the drawing but may be changed or modified so long as such changes or modifications mark no material departure from the salient features of the invention as expressed in the appended claims.

In the drawing:—

Figure 1 shows partly in vertical section and partly in side elevation a straining unit of the type employed in the "Purolator," showing the

improved construction embodying the present invention;

Figure 2 is a view in side elevation of a bushing, per se;

Figure 3 is a plan view of a nut which is made a permanent part of the unit;

Figure 4 is a plan view of the inner face of the central portion of an end plate from which the bushing has been removed.

Referring now more particularly to the drawing wherein like numerals of reference indicate corresponding parts throughout the several views, the numeral 1 indicates as a whole the unit embodying the present invention. This strainer unit which as previously explained forms a part of a device which is designed for use in connection with internal combustion engines for straining the crank case oil, comprises a tubular cloth bag 2 in which is placed a relatively heavy helical spring 3.

Secured to each end of the helical spring is a circular plate 4 which has an aperture 5 centrally therethrough.

In this strainer unit constructed in accordance with the present invention there is permanently secured to the inner face of each of the plates 4, coaxially with the opening 5, a threaded nut 6.

While this is the preferred method of construction it is, of course, to be understood that the invention also contemplates the forming of a threaded opening at this point, as for example, the central part of the disk 4 may be thickened and have the opening 5 threaded.

At the ends of the straining units are bushings 7 and 8 each of which is threaded at one end as indicated at 9, the threads being cut relatively deep so that there is formed at the inner end of the threaded portion a shoulder 10.

The threaded end of each bushing is extended through the adjacent end plate opening for engagement with the threads of the nut 6 and at the upper end of the unit the bushing 7 has its threaded end portion extended through a flat annulus or disk 11 against which the shoulder portion 10 thereof bears. At the lower end of the unit the bushing 8, which is of slightly greater diameter than the bushing 7, passes through an opening 12 in the central part of a relatively large disk which is indicated by the numeral 13. This disk is of materially greater diameter than the straining bag and spring over which it is placed and provided with a series of openings 14 through which oil passes in its passage through the oil cleaner of which the unit 1 forms a part. This form of disk is of standard design and needs no

further description. The bag 2 is provided at each end with an opening 15 of sufficient size to receive the threaded end of the adjacent bushing, and after the bag has been placed in position on the 5 spring body 3 this opening at each end is placed over the adjacent end plate opening and the proper bushing after having its threaded portion extended through the disk which it holds in place, is extended through the end opening of the bag 10 and threadably engaged with the adjacent nut 6. As will be readily seen when the bushings are threaded in as far as they will go each will firmly clamp the adjacent disk against the end of the bag and secure it to the adjacent end plate.

15 At the upper end of the strainer unit the shoulder portion of the bushing 7 will clamp the small flat annulus 11 against the adjacent plate 4 with the underlying part of the bag therebetween and at the lower end of the unit the bushing 8 will force the larger disk 13 inwardly so that the impressed annular rib portion 16 will engage 20 against the adjacent part of the bag and clamp it to the bottom end plate.

From the foregoing it will be readily apparent 25 that by constructing these straining units in the manner herein shown and described, when the cloth bag becomes damaged or worn to the point where it is no longer of use it may be readily removed and replaced by a new bag and the discarding of the entire unit will not be necessary as 30 is at present the case.

Having thus described the invention what is claimed is:—

1. In an oil straining unit having a frame having 35 two ends and provided with an apertured plate at each end and a bag enclosing the frame and plates and having end openings coinciding with said plate apertures, a bushing threadably

secured at one end in the aperture of a plate, and a flat annulus surrounding the bushing and held thereby in clamping relation with the adjacent plate and securing the edge of the adjacent bag opening to the plate. 80

2. In an oil straining unit having a frame having two ends and provided with an apertured plate at each end and a bag enclosing the frame and plates and having end openings coinciding with said plate apertures, a bushing threaded at one end and formed at the inner end of the threaded portion to provide a shoulder, said threaded bushing end being threadably engaged in the aperture of a plate, and a flat annulus surrounding the threaded portion of the bushing and engaged at 90 one side by said shoulder and forced thereby against the edge of the adjacent bag opening to secure the same to said plate. 85

3. In an oil straining unit having a frame having two ends and provided with an apertured plate at each end and a bag enclosing the frame and plates and having end openings coinciding with said plate apertures, an interiorly threaded nut secured against the under side of a plate coaxial with the opening therein, a flat annulus 100 overlying the upper side of the plate and having the edge of the adjacent bag opening interposed between the same and the plate, and a bushing having a portion at one end screw-threaded and formed at the inner end of the screw-threaded portion to provide a clamping shoulder, said threaded portion extending through said annulus, bag opening and plate and threadably engaging said nut and operating to hold the annulus in clamping relation with the plate to secure the 110 bag thereto. 95
